UNITED STATES PATENT OFFICE.

MORGAN J. LANGTON, OF OSWEGO, NEW YORK.

SIDING OR CLAPBOARD SPACING GAGE.

1,261,822.

Specification of Letters Patent. Patented Apr. 9, 1918.

Application filed August 7, 1917. Serial No. 184,876.

To all whom it may concern:

Be it known that I, MORGAN J. LANGTON, a citizen of the United States, residing at Oswego, in the county of Oswego, State of New York, have invented a new and useful Siding or Clapboard Spacing Gage; and I do hereby declare the following to be a full, clear, and exact description of the invention, such as will enable others skilled in the art to which it appertains to make and use the same.

This invention relates to an improved siding, clap board and shingle spacing gage, and one of the objects of the invention is the provision of a gage, which is simple, efficient and practical in construction, and may be used for spacing either clap or siding boards or shingles.

A further object of the invention is to provide a gage which may be used for marking one board to show the point to which the gage may be adjusted for marking the next board, and so on in applying the entire side of a house.

25 A further object of the invention is to provide an improved hanger for the gage.

A further object of the invention is the provision of means whereby a rule may be connected between two gages, for spacing shingles and the like.

In practical fields the details of construction may necessitate alterations falling within the scope of what is claimed.

The invention comprises further features and combination of parts as hereinafter set forth in the specification, shown in the drawings and claimed.

In the drawings:—

Figure 1 is a vertical section through a portion of the side wall of a dwelling, or similar structure showing the application of the gage, whereby clap or siding boards may be spaced.

Fig. 2 is a view in elevation of the structure shown in Fig. 1.

Fig. 3 is a sectional view through a portion of a roof of a house, showing the gage and a rule, the two connected, for spacing the shingles.

50 Fig. 4 is a plan view of the structure shown in Fig. 3.

Referring more especially to the drawings 1 designates a studding of the side wall of a house or the like, and 2 the flap or siding board, and 3 denotes the gage as a whole.

This gage comprises the bar 4, which is designed to be disposed substantially vertically adjacent the side wall of the house. The upper portion of the bar 4 terminates in a curved part 5, a portion 6 thereof being offset from the main part. Secured by a rivet or the like 7 to the bar 4 (which is provided with graduations in inches and fractions thereof), is a cross bar or strip 8, one end of which as shown at 9 is inclined.

An inclined hanger or supporting bar 10 is secured by the pins or rivets or the like 11 and 12 to the outer extremities of the cross bar or strip 8 and the curved portion 5 of the bar 4 respectively. By means of a pin 13 an anchoring spike 14 is pivoted to the upper end of the hanger or supporting bar 10; hence in this manner the gage may be pivotally mounted, by driving the anchoring spike 14 into the studding or other suitable place as may be found advisable. A suitable slide 15 is secured adjustably on the bar 4 by the set screw 16. One end of the slide is inclined as shown at 17. Near the rivets 7 (which secures the bar 8 to the bar 4) the bar 4 is provided with laterally extending ears 18, to which suitable rules 19, such as shown in Figs. 3 and 4 may be secured by the screws 20. In using the siding or clap board gage, the spike 14 is driven into the studding, one gage for each end of the board. The first board or siding to be hung is supported by the slide 15 (which has been previously adjusted as deemed advisable), then the board is nailed. The next 90 board may be supported on the slides of both gages between the first board and the bar 4, and where the upper edge of the cross bar 8 assumes position said board may be marked. The second board is then removed 95 from the slides 15, and inserted below the anchoring spikes 14, in order to rest on the inner ends of the cross bars 8, while the second board is nailed. The process of hanging the second board may be repeated 100 with the third, fourth and fifth boards, and so on until the entire siding of the house is finished. However, the marking of the boards, it is to be noted, may be dispensed with if desired. In spacing shingles the 105 straight edge or rule 19 may be connected to the ears 18 between two gages; then the gages are held in place by driving the spikes into the beams of the roof, after which the shingles are arranged adjacent the straight 110

edge or rule, and then nailed in place. To space the next row of shingles, the gages 15 are adjusted, to abut or contact with the lower edges of the first row of shingles, in 5 which case the straight edge is held disposed at an equal distance and in parallelism with the lower edges of the first row of shingles; then the second row of shingles is arranged in place and nailed. This process is con- 10 secutively repeated until the entire roof is covered with the shingles.

The invention having been set forth what is claimed as new and useful is:—

1. A clap board gage comprising a main 15 bar having calibrations, and provided with a slide adjustable to any one of the calibrations and adapted to support a clap board, a hanger bar connected to the main bar and having means at its upper end to detach- 20 ably secure it to a studding, and a cross bar connecting the hanger bar and the main bar and having one end extending toward the studding of the wall of the building to sup- 25 port a clap board.
2. In a siding gage, a main bar provided with graduations, a slide thereon, means to hold the slide in adjusted positions, whereby the slide may support a siding board, a cross bar connected to the upper part of 30 the main bar and having one end extending toward the studding of the wall of the building to support a siding board, and means connected to the cross bar and the

upper end of the main bar for pivotally mounting said gage on a studding.

35.

3. In a device as set forth, a pair of weather board gages, each comprising a main bar having graduations thereon, a slide adjustable on the lower portion of the main bar to any one of the graduations, means 40 to hold the slide in adjusted positions whereby it may support a weather board, the upper end of said bar having an out- 45 wardly curved portion, a bar extending horizontally across and connected to the main bar and extending toward the studding of the wall of the building to support a weather board, a hanger bar inclined downwardly and outwardly at an acute angle to the studding of the wall of the building and 50 having its lower end connected to the outer end of the horizontal bar and the outer end of the curved portion of the main bar, a spike adapted to be driven into the studding and to which the upper end of the angularly disposed bar is pivotally mounted, the side of the main bar having an ear, and a straight edge connecting the ears of the main bars of both gages.

55.

In testimony whereof I have signed my 60 name to this specification in the presence of two subscribing witnesses.
